[57] **CLAIM**

The ornamental design for a livestock roughage feeder, as shown and described.

DESCRIPTION

FIG. 1 is a perspective view taken from the top, front and left side of a livestock roughage feeder showing our new design;

FIG. 2 is a left side elevational view thereof, the right side being a mirror image of the side shown;

FIG. 3 is a front elevational view thereof;

FIG. 4 is a rear elevational view thereof;

FIG. 5 is a top plan view thereof; and

FIG. 6 is a cross sectional view taken on line 6—6 of FIG. 1.
